UNITED STATES PATENT OFFICE.

OLIVER P. WILHELM AND JOSEPH F. POSDAL, OF MICHIGAN CITY, INDIANA, ASSIGNEES
OF ONE-FOURTH TO SANTFORD W. WILHELM, OF MICHIGAN CITY, INDIANA, AND
ONE-FOURTH TO BEN LOEWENTHAL, OF CHICAGO, ILLINOIS.

OIL OR GAS FURNACE.

1,295,944.

Specification of Letters Patent.

Patented Mar. 4, 1919.

Application filed June 28, 1917. Serial No. 177,471.

To all whom it may concern:

Be it known that we, OLIVER P. WILHELM and JOSEPH F. POSDAL, citizens of the United States, and residents of the city of Michigan City, in the county of Laporte and State of Indiana, have invented certain new and useful Improvements in Oil or Gas Furnaces; and we do hereby declare that the following is a full, clear, and exact description of the same, reference being had to the accompanying drawings, and to the numerals of reference marked thereon, which form a part of this specification.

This invention relates to improvements in oil furnaces.

It is an object of this invention to provide an oil or gas furnace in which various groups of material to be heated, may be placed, and in which all the chambers or groups of material may be heated simultaneously or any one independently of the others, or any combination of chambers or groups of material may be heated or treated independently of the others.

It is further an object of this invention to provide a furnace in which a suitable deflecting fire chamber is provided which, acting in conjunction with a universal burner, is adapted to throw the heat to any part or parts of the furnace independently of the other parts.

It is further an object of this invention to provide a universal oil or gas jet or burner adapted for adjustment to direct the spray of combustible gases to any point on a flame deflector, and a deflector which is so shaped to coöperate therewith as to deflect the flame to the desired part or parts of the furnace.

It is also an object of this invention to provide a novel fire and deflecting chamber which is so constructed as to deflect the intense flames or heat accurately to the part or parts of the furnace desired without wasting a large percentage of the heat energy by deflecting the flames to other parts of the furnace.

It is furthermore an object of this invention to provide a furnace in which various materials or piles of the same material may be successively heated or treated as the consumption requires.

Other and further important objects of the invention will be apparent from the disclosure in the specification and drawings.

The invention (in a preferred form) is 55 illustrated in the drawings and hereinafter more fully described.

On the drawings:

Figure 1 is a front elevation of a furnace embodying our invention.

Fig. 2 is a transverse vertical section thereof.

Fig. 3 is a horizontal section thereof taken above the fire chamber.

Fig. 4 is a vertical section taken centrally 65 of the section shown in Fig. 2.

Fig. 5 is an enlarged detail of the burner shown in elevation.

Fig. 6 is an enlarged detail section of the burner with parts in elevation.

Fig. 7 is a section taken on line 7—7 of Fig. 6.

Fig. 8 is an enlarged fragmentary detail of the oil feed spraying jet.

Fig. 9 shows a furnace embodying our invention provided with a modified form of burner.

Fig. 10 is an enlarged fragmentary detail section of the burner thereof showing the universal oil feed pipe in elevation.

Fig. 11 is a section taken on line 11—11 of Fig. 10.

Fig. 12 is an enlarged fragmentary detail of the method of connecting the pipes for universal movement of the feed pipe.

Fig. 13 is a horizontal section of a furnace provided with a modified form of fire chamber.

Fig. 14 is a transverse vertical section through the furnace showing the modified 90 fire chamber.

As shown on the drawings:

The reference numeral 1, indicates a furnace as a whole which is constructed exteriorly in any preferred manner, and is provided with a suitable number of apertures 2, as shown, four in number, through which the material is inserted and withdrawn from the heating chambers 3—4, one located on each side of the center of the furnace, as 100 shown clearly in Fig. 2. The interior of the furnace is lined with fire brick of suitable kind, and the bottom fire brick is provided with the heating chambers 3—4, which are respectively provided with walls 5 and 105

6, to retain and prevent the material heated, as, for instance, rivets, from falling into a fire chamber 7. The fire chamber 7, has the

bottom and side walls peculiarly shaped and arranged for deflecting the flame and heat to the desired part or parts of the furnace. As shown, a centrally disposed deflector rib 8, 5 triangular in cross-section, extends the full depth of the furnace, and from the bottom of said rib 8, walls 9, are formed in compound curve, that is, are curved outwardly and upwardly from the base of the rib 8, 10 then substantially vertical for a short distance, then curved outwardly, forming the retaining walls 5 and 6, before mentioned.

Any suitable top or covering 10, is provided, which has a downwardly opening 15 axial passage centrally disposed over the deflecting rib or wall 8. Extending into said passage is a universal burner which is so adjustable as to direct the flame against any point in the fire chamber. An air pipe 11, is 20 shown, to which is connected at substantially right angles a pipe 12, having a flange 13, integral with the lower end thereof. The flange 13 rotatably supports a part of the burner comprising a pipe 14, having an upwardly directed exteriorly threaded enlarged upper end or cup 18, adapted to fit over the flange 13, and to receive a suitable packing 15, and jam washer 16, therein. The packing 15 and the washer 16, are 25 tightly clamped in place by a cap or collar 17, disposed around the pipe 12, and threaded on the upper end of the cup 18. The lower end of the pipe 14, is provided with a flange 19, on which is supported the 30 pipe 20. Said pipe 20, is provided with an enlarged exteriorly threaded upper end or cup 21, between which and the pipe 14, a suitable packing 22, and jam washer 23, are secured and firmly held in place to form a 35 tight joint by means of the flanged collar or cap 24, which threads on the cup 21 end of pipe 20.

Journaled in the rotatable pipe 14, in any suitable manner, is a shaft or spindle 25, to 40 which is secured a half butterfly valve 26. A wheel 27, is secured on the outer end of said shaft and fastened to said wheel 27, is a spring arm or pawl 28, adapted to engage the marked segment 29, to hold the valve in 45 any adjustment. An oil or gas supply pipe 30, connects with any suitable source of supply, and is provided with a valve 31, for controlling the supply therethrough. An oil or gas spraying nozzle 32, is attached to 50 the pipe 30, and extends downwardly in the air pipe 12, to within a suitable distance above the butterfly valve. Said spraying nozzle, as shown in detail in Fig. 8, has a 55 plug 33, in the end thereof and apertures 34, 60 open tangentially downwardly into a deflector and drip cup 35, secured on the end of the nozzle.

In the construction shown in Figs. 9 to 12, inclusive, the furnace is constructed the 65 same as hereinbefore described with the ex-

ception that the burner is constructed differently. As shown, an air pipe 36, extends through the passage in the cover 10, said pipe being provided with an externally threaded boss 37, adapted to have a jam nut 70 38, threaded thereon. The boss 37, and jam nut 38, are complementally ground to form a seat for the ball 39, on the supply pipe 40, to form a ball and socket joint, and said jam nut is cut away to permit free movement of the pipe 40, in any direction. A downwardly directed nozzle or spray pipe 41, is secured to the inner end of the pipe 40, as shown.

For the purpose of permitting pipe 40, 80 being swung in any direction to direct the nozzle as desired, a pipe 42, is provided, which leads to the source of supply, and is provided with a controlling valve 43. Any standard coupling 44, is secured to the pipe 85 42, that will permit turning of the pipe 45, and said pipe 45, is likewise connected to pipe 46, by means of a coupling 47, which will permit swinging motion of said pipe. A similar coupling 48, connects pipes 46 and 90 49, and all of these couplings co-act to permit pipe 40, being adjusted universally to direct the end of the nozzle as desired.

In Figs. 13 and 14, we have shown a modified form of fire chamber. Instead of a 95 long fire chamber, as shown in Fig. 2, we provide a circular or round fire chamber which is shaped to provide an upwardly directed cone deflector 50, from the bottom of which the wall 51, of the fire chamber is 100 curved downwardly, outwardly and upwardly. Said wall is substantially vertical for a short distance, and terminates in an outwardly curved wall 52. Retaining walls 53-53 are provided to prevent the articles 105 being treated from falling into the fire chamber.

The operation is as follows:

In the construction shown in Figs. 1 to 8, inclusive, the articles to be heat treated or 110 heated are inserted into the heating chambers 3-4, through the openings 2, and we will assume that the heat is desired to be directed uniformly to all points of the heating chambers. In this case, the butterfly 115 valve is fully opened, and the valve 31 in the supply pipe 30, is opened. The oil or gas being under pressure is admitted to the nozzle 32, and is sprayed through the apertures 34, and deflected by the cup deflector 35, outwardly against the walls of the burner where the air from the pipe 11, is carbureted with the oil or gas to form a fuel gas which is forced under pressure through 120 the pipe, and is ignited as is usual in burners of the Bunsen type. The ignited gas is forced under pressure directly downwardly on the deflector wall 8, which in turn evenly distributes the flame and deflects the same 125 evenly against the walls 9, of the fire chamber. 130

ber, from whence it passes over the retaining walls 5 and 6, into the heating chambers.

If it is desired to heat one end of one chamber only, the half butterfly valve is operated to half close the burner and in this position the burner is rotated until the open half of the burner is directed toward the end of the chamber to be heated. When 10 adjusted this way, all of the flame is directed to one side and one end of the deflector wall 8, from where in turn the flame is directed to the desired chamber. If the same ends of two different chambers are to 15 be heated simultaneously, the burner is turned until the open half thereof is directed equally to the chambers, that is, the butterfly valve lies transversely of the deflector wall with the open side toward the 20 ends of the chambers to be heated. In this position, the flame is directed toward corresponding ends of the fire chambers and is distributed equally on both sides of the deflector.

25 Now, assuming that material in the same ends of two chambers is to be treated simultaneously but at different degrees, the burner is rotated so that the open half of the valve is diagonally directed across the deflector wall in which position the flame is divided by the deflector and deflected to the same ends of the chambers but at different degrees. It will be seen by the construction set forth 30 that any heating chamber or combination thereof can be heated independently of the others, and that articles in different chambers may be consecutively treated while those previously treated are being used, or in fact, any desired heating arrangement is obtainable. The retaining walls, of course, prevent any of the articles such as rivets, 35 knuckles, or any other articles from falling into the fire chamber.

In the construction shown in Figs. 9 to 45 12, inclusive, the same results are obtained by operating the pipes 40 and 49, to swing the nozzle 41, as desired. This nozzle can be universally adjusted within the necessary limit of adjustment required by virtue of the 50 connections 44, 47 and 48, hereinbefore set forth.

In the construction shown in Figs. 13 and 55 14, the burners are of any of the types described herein, and the operation of the fire chamber and deflector wall is substantially as hereinbefore set forth.

We are aware that various details of construction may be varied through a wide range without departing from the principles 60 of this invention, and we therefore do not purpose limiting the patent granted otherwise than necessitated by the prior art.

We claim as our invention:

1. In a furnace of the class described, a 65 fire chamber centrally disposed therein, a

deflector therein, heating chambers arranged on opposite sides of and around the fire chamber, and a burner co-acting with the deflector and fire chamber to apply the heat to one chamber independently of the other. 70

2. In a furnace of the class described, a fire chamber, heating chambers arranged around the same, an adjustable burner, and a deflector in the fire chamber adapted to co-act with said burner to direct the intense 75 heat to one heating chamber independently of the other, or to both of the heating chambers.

3. In a furnace of the class described, a plurality of heating chambers, a fire chamber, a retaining wall between said chambers, a deflecting wall centrally disposed in the heating chamber, and an adjustable burner adapted to throw a flame against the deflector wall at any point thereof. 80 85

4. In a device of the class described the combination of a furnace having heating chambers therein and an opening through the wall thereof into each chamber, a fire chamber, and co-acting adjustable burner 90 and deflecting means for directing the intense heat to one or both chambers.

5. In a device of the class described, a furnace, a fire box therein, heating chambers in said furnace, and a deflector in the fire 95 box, said fire box having curved deflecting walls extending from the bottom of the deflector to the edge of the heating chambers.

6. In a device of the class described, a furnace, a fire box therein, heating chambers in said furnace, a deflector in the fire box, 100 said fire box having curved deflecting walls extending from the bottom of the deflector to the edge of the heating chambers, and serving to separate the fire box from the 105 heating chambers.

7. In a device of the class described, a furnace, a fire box therein, heating chambers in said furnace, a tapered deflector in the fire box, said fire box having curved deflecting surfaces, a retaining wall separating the fire box from the heating chambers, and an adjustable burner adapted to direct the flame against the deflector at any point 110 thereof. 115

8. In a device of the class described, a furnace provided with heating chambers, of a deflector therein, and an adjustable burner in said furnace co-acting with the deflector adapted to direct the heat equally to both 120 chambers, wholly to either chamber independently of the other, or equally or un-equally to corresponding ends of the chambers.

9. In a device of the class described, a 125 furnace provided with heating chambers and openings through the walls thereof to charge the heating chambers, a fire chamber disposed in said furnace, a burner in said furnace, said burner embracing adjustable parts 130

and a deflector in the fire chamber adapted to co-act with said adjustable parts to receive the flame against any point thereof and deflect the flame to either or both 5 chambers.

10. In a furnace, a plurality of heating chambers, a fire chamber having its walls shaped to deflect flames thereinto, a deflector in the fire chamber, and a burner adjustable 10 to direct the flame directly downwardly on

the deflector or at various angles to the deflector.

In testimony whereof we have hereunto subscribed our names in the presence of two subscribing witnesses.
